BASE-BOARD HEATER OR SIMILAR ARTICLE

Norman B. Wenig, Yonkers, N.Y.
(230 Manida St., Bronx 59, N.Y.)

Filed Aug. 23, 1961, Ser. No. 66,473

Term of patent 14 years

(Cl. D81—21)

FIG. 1 is a front perspective view of a base-board heater, or similar article, showing the front and the top and a side of my new design;

FIG. 2 is a fragmentary plan view of one end thereof; and

FIG. 3 is a sectional view taken on the line 3—3 of FIG. 1.

The rear is substantially plain, and the undisclosed side is a mirror-image of the side shown in FIG. 1.

I claim:

The ornamental design for a base-board heater or similar article, substantially as shown and described.
